BATTERY WATER DISPENSER

Robert W. Olsen, Hinsdale, Ill., assignor to
Efficiency Dispensers Corporation

Filed June 18, 1973, Ser. No. 371,279

Term of patent 14 years

Int. Cl. D9—01

U.S. Cl. D9—53

FIG. 1 is a side elevational view of a battery water dispenser showing my new design;

FIG. 2 is an end elevational view taken from the right-hand end of FIG. 1;

FIG. 3 is an end elevational view taken from the left-hand end of FIG. 1;

FIG. 4 is a top plan view; and

FIG. 5 is a bottom plan view.

I claim:

The ornamental design for a battery water dispenser, as shown.
